DISPLAY BOX

Dougal S. Logan, Pawtucket, R. I., assignor to
 Shaw Paper Box Company, a corporation of
 Rhode Island

Application January 5, 1939, Serial No. 249,475

3 Claims. (Cl. 206—44)

This invention relates to a display box and has for one of its objects to provide a box which may have the article holding portion thereof inclined at an angle to the horizontal surface upon which the box is supported to better display the merchandise within the box.

Another object of the invention is to provide a novel and compact arrangement whereby the contents-holding portion of the box may be adjusted to varying angles of inclination that the merchandise carried therein may be displayed at the most convenient and best observable angle to the supporting surface for the box.

Another object of the invention is to provide a tray-like article-holding member which is telescoped within an outer similar member with a slide which is movable along one member to adjustably support the companion member in desired position.

Another object of the invention is to provide such a structure which will enable a cover to be placed over the entire contents-holding portion for closing the same.

With these and other objects in view, the invention consists of certain novel features of construction, as will be more fully described, and particularly pointed out in the appended claims.

In the accompanying drawing:

Fig. 1 is a perspective view of the box in inclined position;

Fig. 2 is a perspective view of the two tray members or sections in telescoped relation;

Fig. 3 is a perspective view of the support member;

Fig. 4 is a perspective view of the parts of Figs. 2 and 3 assembled and with one part in inclined position;

Fig. 5 is a sectional view showing the hinge relation of the two tray-like members;

Fig. 6 is a sectional view on line 6—6 of Fig. 4 illustrating the support member as moved to a position to incline one of the tray members with reference to the horizontal support upon which the box may rest;

Fig. 7 is a sectional view of the structure shown in Fig. 4 with the cover in position;

Fig. 8 is a sectional view similar to Fig. 6 but showing the support member as in telescoping relation with the inclinable member;

Fig. 9 is a sectional view similar to Figs. 6 and 8 but illustrating a different arrangement of the support member; and

Fig. 10 is a sectional view on substantially line 10—10 of Fig. 9.

It is frequently desirable in the use and forma-

tion of display boxes to provide an arrangement whereby the merchandise may be displayed at an angle to more quickly attract the eye of the passer-by and to more effectively display the merchandise contained in the box. In order that this may be effectively arranged in a simple manner, I have provided a pair of tray-like members which are hinged together and, additionally, provide a sliding support on one of the members so that when in certain positions it will engage parts of the other member and form a support and thus prevent it from fitting fully within the other member whereby one of the members is supported or in inclined relation; and the following is a more detailed description of the present embodiment of this invention, illustrating the preferred means by which these advantageous results may be accomplished:

With reference to the drawing: 10 designates the outer section or member of tray-like form which consists of a bottom wall 11, opposite end walls 12—12' and opposite side walls 13—13'. Within this member 10 I provide a second member 14 which is of a somewhat smaller size than was previously described and which likewise consists of a bottom wall 15, opposite end walls 16—16' and opposite side walls 17—17'. These two members, 10 and 14, fit together in a telescoping relation but the member 14 is of a length considerably less than the length of the member 10, so that when the end walls 12 and 16 are together, the opposite end walls 12' and 16' are spaced a substantial distance apart.

A support member 18 consists of opposite walls 19—19' and 20—20', forming a frame-like structure which is of a size and shape to closely fit and telescope the member 10; that is, the walls 20—20' are substantially the distance apart of the walls 13—13' and the walls 19—19' are substantially the distance apart of the height of the walls 12—12' and 13—13', while the opening 21 through the frame enables it to slide along the member 10. The width of the walls which form the band-like member 18 are such as to be substantially the dimension of the difference between the lengths of the members 10 and 14 so that this member 18 will fit upon the member 10 as illustrated in Fig. 4.

The member or sections 10 and 14 are provided with a hinge connection 22 as illustrated in Figs. 2, 4, 5 and 6 whereby the sections 10 and 14 may swing one relative to the other as illustrated in Figs. 1 and 6, and when swung about this hinge the support 18 may be positioned beneath the member 14 and by sliding the member 55

18 along the member 10, different distances from the hinge, the tray member of section 14 to be inclined various angles with reference to member 10 so as to provide the desired inclination 5 for this member 14.

A cover member 23 may be provided consisting of a top 24 and opposite sides 25 to telescope over the sections shown in telescoped relation as shown in Figs. 2 and 4 for housing the contents of the 10 tray section 14.

In some cases, instead of the support telescoping section 10 as heretofore illustrated, and described, this support may telescope the section 14 as at 18' in Fig. 8 whereupon the support 15 member will then rest upon the side walls 13-13' in order to obtain its support. In other cases, however, the support member 18'', as shown in Figs. 9 and 10 may be contained within the walls 13-13' and slide along within the box beneath 20 the tray or section member 14 without embracing the outer member 10.

In all forms the support member being slidable will adjust the inclination of the tray member to its desired height or degree of inclination as 25 occasion may require.

The foregoing description is directed solely towards the construction illustrated, but I desire it to be understood that I reserve the privilege of resorting to all the mechanical changes 30 to which the device is susceptible, the invention being defined and limited only by the terms of the appended claims.

I claim:

1. In a display box, a body formed of two tray 35 sections, one fitting within the other and each having a bottom wall and opposite side walls, corresponding side walls at one side having their edges adjacent, hinge means to connect said

walls, a rectangular fence-like member engaging the bottom wall and opposite side walls of one member and slidably guided by the member in movement therealong and with one of its walls positioned between said tray members for varying 5 the degree of angular elevation of the sections about the hinge means through an arc of approximately a quarter of a revolution.

2. In a display box a body formed of two tray sections, one fitting within the other and each 10 having a bottom wall and opposite side walls, a side wall of one section having its edge adjacent to a corresponding side wall of the other section and hinged thereto, and a rectangular fence-like enclosed support member beneath the inner section 15 for contacting it, said support being frictionally slid able along the outer section and guided thereby to incline the inner section to a degree of elevation dependent upon the position of the support member along the member which 20 guides it.

3. In a display box a body formed of two tray sections, one fitting within the other and each having a bottom wall and opposite side walls, a side wall of one section having its edge adjacent 25 to a corresponding side wall of the other section and hinged thereto, the inner section being shorter than the outer section, and a rectangular fence-like enclosed support member of a width equal to the difference in length of the sections beneath the inner section for contacting it, said support being frictionally slid able along the outer section and guided thereby to incline the inner section to a degree of elevation dependent upon the position of the support member along the member which 30 guides it.

DOUGALD S. LOGAN.
